(57) **CLAIM**

I claim the ornamental design for a beverage container, as shown and described.

DESCRIPTION

FIG. 1 is an isometric, top view of beverage container showing my new design;

FIG. 2 is a front view thereof;

FIG. 3 is a left side view thereof;

FIG. 4 is a rear view thereof;

FIG. 5 is a right side view thereof;

FIG. 6 is a top view thereof; and,

FIG. 7 is a bottom view thereof.

The broken lines in the drawings showing a cap are included for the purpose of illustrating environmental structure and form no part of the claimed design.
